ELECTRICAL REMOTE CONTROL BOX FOR TELEVISION CAMERA

Angelo Nicosia, Glen Cove, N.Y., assignor to Zoomar,
Inc., Glen Cove, N.Y., a corporation of New York

Filed Jan. 25, 1968, Ser. No. 10,305

Term of patent 7 years

(Cl. D26—5)

FIG. 1

FIG. 2

FIG. 3

FIGURE 1 is an isometric view of an electrical remote control box for television camera, showing my new design,

FIGURE 2 is an isometric view taken from the rear thereof; and

FIGURE 3 is a bottom plan view thereof.

I claim:

The ornamental design for an electrical remote control box for television camera, substantially as shown.
